UNITED STATES PATENT OFFICE.

KATHERINE B. LEDEBETTER, OF REDMOND, OREGON.

OUTDOOR BED.

1,196,554.

Specification of Letters Patent. Patented Aug. 29, 1916.

Application filed April 28, 1915. Serial No. 24,529.

To all whom it may concern:

Be it known that I, KATHERINE B. LEDEBETTER, a citizen of the United States, residing at Redmond, in the county of Crook 5 and State of Oregon, have invented new and useful Improvements in Outdoor Beds, of which the following is a specification.

An object of the invention is to provide a bed or sleeping berth for use in camping 10 and out of doors, the bed being particularly useful in the summer season or in countries where the temperature is usually high so that a person occupying the bed, by the rapid evaporation of moisture due to a high 15 temperature, will be kept cool.

The invention contemplates, among other features, the provision of a bed which is in the nature of a tent-like chamber or compartment adapted to have its roof or sides made 20 of a moisture absorbing material and supplied with moisture which, being rapidly evaporated by the high temperature of the climate, will cause the interior of the compartment to be cooled, thus lowering the 25 temperature therein.

In the further disclosure of the invention reference is to be had to the accompanying drawings, constituting a part of this specification, in which similar characters of reference denote corresponding parts in all the 30 views, and in which:

Figure 1 is a perspective view of the structure; Fig. 2 is a vertical transverse sectional view; and Fig. 3 is a fragmentary vertical 35 longitudinal sectional view.

Referring more particularly to the views, I provide a frame 10 which includes a series of uprights 11 and cross pieces 12, a roof 13 and sides 14, together with a back 15 and 40 a front 16 arranged upon the frame, the sides, roof and back and front being preferably made of a moisture absorbing material, such as a loose mesh canvas or the like and forming a compartment 17. Screens or similar closures 18 are preferably connected 45 with the uprights of the frame at their lower portions and adjacent the lower longitudinal edges of the sides and back and suitably supported on the frame within the compartment 50 is a bed body 19 which may be of any convenient material and structure, said bed

body being spaced from the floor or ground 55 and connecting with the frame along the line of connection of the sides and back with the screens 18. The sides 14 may be in the nature of curtains to be rolled up and secured by suitable straps 20 and the frame 10 60 includes a ridge-pole 21 which supports a longitudinally extending trough 22 preferably extending throughout the length of the compartment but exteriorly thereof. A series of wicks or other moisture absorbing 65 members 23 are adapted to have their inner ends lie within the trough, which is filled with water, the outer ends of the wicks lying upon the roof 13. Now it will be clearly seen that the wick absorbing the water from 70 the trough will convey the same to the roof and thus the moisture will also be conveyed to the sides so that the roof and sides, as well as the front and back, becoming moist from the water in the trough will, due to the 75 high temperature, result in a rapid evaporation of the moisture from said roof, sides, back and front, thereby resulting in the lowering of the temperature within the compartment so that the occupant of the compartment will be kept cool during the night 80 season or when occupying the compartment.

The frame 10 is preferably fashioned so that it can be folded up if desired, the sides, back and front being made of cloth as mentioned so that the entire structure can be 85 easily folded into a compact package and carried along as a part of a camping outfit.

Having thus described my invention, I claim:

1. A bed embodying a frame including a ridge pole, a cover supported by said frame, a trough carried on the frame and disposed above and in superposed parallel relation to the ridge pole of the frame, and wicks in said 95 trough and overhanging the opposite longitudinal edges thereof at spaced intervals throughout the length of the trough and extending upon the covering of the frame at points to opposite sides of the ridge pole. 100

2. A bed comprising a frame, sides, a back, a front and roof, said sides, back, front and roof being supported on said frame and forming a compartment, a covering for said frame, a moistener disposed 105

above the plane of the covering and in superposed relation with the longitudinal center of said frame, screens on said frame at the lower portion thereof, and a bed body supported on the frame in said compartment in spaced parallel relation to the floor or ground upon which the frame reposes.

In testimony whereof I affix my signature in presence of two witnesses.

KATHERINE B. LEDBETTER.
